STORAGE RECEPTACLE WITH SLIDING CLOSURE

Irving Blechman, Bronx, N. Y.

Application November 13, 1936, Serial No. 110,663

1 Claim. (Cl. 229—43)

This invention relates to receptacles constructed of light weight, inexpensive sheet material and has particular reference to a receptacle of the said character having a sliding closure preferably of a rigid type and with means for guiding the same during the opening and closing movements thereof.

The invention provides a receptacle of the said character which is so constructed and arranged as to insure a sealing engagement with the closure thereof when the same is in closed condition so as to preclude the entrance into the receptacle of insects, dust and other agencies injurious to articles stored therein.

15 The invention further comprehends a receptacle having a sliding closure and with means constituting a guide for the same during the opening and closing movements thereof and which provides a seal at the edges thereof when in closed condition and functions to frictionally retain the closure in closed condition.

20 The invention more specifically embodies a hollow body structure including a rear wall, forwardly directed side walls and a double ply front wall connected to the side walls at the free longitudinal edges thereof, the plies of which are provided with registering openings defining a mouth for admitting to and removing articles from the hollow body structure, together with a closure 25 panel slideable between the said plies into and out of closing relation with the said mouth.

25 With the foregoing and other objects in view, reference is now made to the following specification and accompanying drawing in which there is illustrated the preferred embodiment of the invention, while the appended claim covers modifications and variations thereof which fall within the scope of the invention.

30 In the drawing:

40 Fig. 1 is a front view of a receptacle constructed in accordance with one form of the invention.

Fig. 2 is a vertical sectional view therethrough taken approximately on line 2—2 of Fig. 1.

45 Fig. 3 is a horizontal sectional view taken approximately on line 3—3 of Fig. 1.

Fig. 4 is a similar view taken approximately on the line 4—4 of Fig. 1.

50 Referring to the drawing by characters of reference, the receptacle is preferably constructed of light weight, inexpensive sheet material such as corrugated cardboard, paperboard and the like, and includes a rear wall 10, oppositely disposed side walls 11 and 12, a front wall 13 and opposite end walls 14 and 15. The front wall 13 is of double ply construction comprising inner and

outer plies 16 and 17, respectively which have longitudinally extending rearwardly directed flaps 18 at the lateral side edges thereof which overlie the outer face of the side walls 11 and 12 respectively adjacent the forward free edges thereof and are secured thereto by any desired means such as the fastening elements 19.

The said plies 16 and 17 of the front wall 13 are provided with registering rectangular-shaped openings 20 in the upper portion thereof with the lateral side edges of the openings spaced from the longitudinal side edges of the said front wall and with the upper edges of the openings spaced from the upper edge of the said wall to provide a wall portion framing the openings in the plies 16 and 17. The openings 20 in the said plies 16 and 17 provide a mouth for admitting to or removing articles from the container. A closure panel 21, preferably of stiff or non-flexible material, is disposed between the said plies and slideable therebetween from an open relation below the said mouth or openings 20 to closed relation with the said mouth or openings with the marginal edges thereof extending beyond the edges of the mouth or openings and between and overlapped by the framing portions of the plies 16 and 17. The securing of the plies 16 and 17 to the side walls 11 and 12 is such as to tension the mouth framing portions of the plies so as to frictionally grip the lateral side portions of the closure 21 to effectively seal the same when the closure is in closed relation with the mouth or openings 20 and to retain the closure in any position to which it is shifted.

The end walls 14 and 15 abut against the opposite end edges of the plies 16 and 17 to seal the end walls and the space between the plies of the front wall.

Preferably the walls 10, 11 and 12 of the receptacle are constructed from a length of stock to provide an integral body section with the said walls swingably and collapsibly connected together so that the same may be disposed in compact arrangement for storage or shipment. The end walls 14 and 15 preferably include marginal flanges 22 which telescopically fit over the opposite ends of the rear, front and side walls and suitable removable fastening elements 23 retain the same in assembled relation. Any suitable manipulating means, such as the handle 24 is secured to the closure 21 for shifting the same to 50 and from its open and closed positions.

What is claimed is:

In a receptacle, a hollow body structure including a rear wall, forwardly directed side walls, a double-ply front wall each having rearwardly

directed flaps at the lateral side edges thereof secured to the side walls respectively adjacent the forward free edges thereof, and top and bottom walls, the plies of said front wall having register-
5 ing openings defining a mouth for admitting to and removing articles from the hollow body struc-
ture, the edges of said openings being spaced from the edges of the plies of the front wall to provide
10 wall portions framing the said openings and a closure panel disposed between the said plies of the front wall and slidable therebetween into

and out of closing relation with the said mouth, with the marginal edges of the panel overlapped by the said framing portions to seal the same when in closed relation with the mouth and said plies of the front wall being compressed in close relation at the lateral side edges thereof so as to tension the mouth-framing portions of the plies to frictionally retain the closure in shifted position. 5
